UNITED STATES PATENT OFFICE.

ALEXANDER A. GUZEL, OF HOT SPRINGS, VIRGINIA.

SPARK-PLUG.

1,315,935.

Specification of Letters Patent.

Patented Sept. 9, 1919.

Application filed December 15, 1917. Serial No. 207,272.

To all whom it may concern:

Be it known that I, ALEXANDER A. GUZEL, a citizen of the United States of America, residing at Hot Springs, in the county of Bath and State of Virginia, have invented certain new and useful Improvements in Spark-Plugs, of which the following is a specification.

This invention relates to an improved spark plug for use in conjunction with internal combustion engines, and has for an object to provide a sight feed spark plug, or a spark plug wherein the passage of the spark between the points of the electrodes may be ascertained without the removal of the plug from the engine cylinder.

Another object of the invention is to so position the "sight spark" electrodes that the "sight spark" will not tap or materially reduce the strength of the current to the main electrodes.

Still another object of my invention is the provision of an electrode which will not oil up or carbonize.

Other and further objects will be in part described and in part apparent as the description is proceeded with.

For a full understanding of the invention reference is had to the following description and accompanying drawing, in which:

Figure 1 is a side elevation of my invention partly in section, and

Fig. 2 is a bottom plan view of same.

Referring more particularly to the drawings in which like reference numerals refer to corresponding parts throughout the several views 1 indicates the body of the plug of suitable insulating material preferably mica, the use of mica being preferred because of its non brittle nature. The body 1 is provided with a longitudinal opening 2 through which extends one of the primary electrodes 3 to the upper end of which is attached the lead wire 4 by means of a thumb nut 5. The lower end of the body is housed in a metallic casing 6 having sight openings 7 therein suitably inclosed by a transparent tube 8 snugly seated between washers 9 of non conducting material. The purpose of the transparent tube is to exclude water and oil from the interior of the casing.

A disk 10 of asbestos or other suitable heat resisting and insulating material is clamped against the lower extremity of the body 1 by an internal flange 13 formed upon a hollow screw member or sleeve 11 screwed to the

metallic casing as at 12 while a nut 14 clamps the casing 6 in place.

Screwed within the end of the hollow member or sleeve 11 is a concave electrode holder 14^a and adapted to seat loosely upon the perforated bottom wall of which holder is a movable spherical, primary electrode 15. A lock screw or pin 16 locks the electrode holder in adjusted position.

The electrode 3 projects through and below the asbestos disk or washer 10 and is secured at its end to a metallic coupling 17 having a platinum sparking point or terminal 18. One of the secondary or sight spark electrodes 19 having its lower end connected to the coupling extends upwardly through a channel 20 in the body member and outwardly to a point adjacent one of the sight openings 7 in the casing 6. The other secondary or sight spark electrode comprises a pin or the like 21 seated in the sleeve 11 and having its upper end projecting upwardly through the asbestos washer 10 into the casing 6 into close proximity to the curved extremity of the electrode 19. The sleeve 11 screws into the explosion chamber of an engine cylinder (not shown) as will be readily understood.

The operation of the plug is as follows: Current passes through the lead 4 into the electrode 3 and coupling 18 and thence via the path of least resistance across the gap therebetween to the electrode 15, thus producing the explosion spark at the same time a current sufficient to cause a spark passes through the sight spark electrode and across the comparatively wide gap between said last mentioned electrode into the sight spark electrode 21 where it is grounded in the sleeve 11 thus completing the circuit. It is observed, in this connection, that the spark in the ignition-chamber containing the primary electrode 15 being under engine-compression and that the spark-chambers of the secondary electrodes being under only atmospheric pressure, the current will be sufficiently intensive or great to result in a surge spark at the gap between the secondary electrodes for observation at that point as called for herein. The back pressure from the explosion chamber through the opening 22 formed in the bottom wall of the electrode holder 14^a has a tendency to agitate the electrode 15 thus preventing carbon and oil from accumulating thereon.

Instead of employing the coupling mem-

ber 17 it is obvious that the electrode 19 may be a continuation of the electrode 3, in which event the bend in the latter will be provided with a suitable and preferably platinum 5 sparking point.

Having thus described my invention what I desire to secure by Letters Patent is:

In a spark plug, a body of insulating material having a longitudinal opening, a metallic member for supporting said body, a casing of conducting material inclosing a portion of said body and insulated from said support, said casing having windows therein, a perforated member of conducting material secured to said support, a movable elec-

trode supported by said perforated member, an electrode rod in said longitudinal opening, a coupling member of conducting material between said electrode-rod and said movable electrode having a sparking point 20 in proximity to said movable electrode, and secondary electrodes, one of the same being connected to said coupling member, the primary electrodes comprising said electrode-rod and movable electrode and secondary electrodes, being adapted to be subjected to engine compression and atmospheric pressure, respectively.

In testimony whereof I affix my signature,

ALEXANDER A. GUZEL.
